DESIGN FOR A HOUSING FOR A POWER LAWN MOWER

John O. Smither, Fort Scott, Kans.

Application July 3, 1945, Serial No. 120,504

Term of patent 14 years

(Cl. D40—1)

To all whom it may concern:

Be it known that I, John O. Smither, a citizen of the United States of America, residing at Fort Scott, Bourbon County, and State of Kansas, have invented a new, original, and ornamental Design for a Housing for a Power Lawn Mower, of which the following is a specification, reference being had to the accompanying drawing, forming a part thereof wherein:

Figure 1 is a side elevational view of a housing for a power lawn mower, showing my new design.

Figure 2 is a top plan view.

Figure 3 is a front elevational view.

Figure 4 is a rear elevational view.

I claim:

The ornamental design for a housing for a power lawn mower, as shown.

JOHN O. SMITHER.
